UNITED STATES PATENT OFFICE.

GORDON KAY, OF NEW YORK, N. Y., ASSIGNOR TO CARL G. PERCY, OF YONKERS, NEW YORK.

COLLAPSIBLE-CARTON DISPLAY.

1,392,337.

Specification of Letters Patent.

Patented Oct. 4, 1921.

Application filed December 23, 1920. Serial No. 432,699.

To all whom it may concern:

Be it known that I, GORDON KAY (formerly known as Gus MAJOR KAISER) a citizen of the United States, and resident of 5 New York city, in the county of New York and State of New York, have invented certain new and useful Improvements in Collapsible-Carton Display, of which the following is a specification.

10 This invention relates to collapsible carton display, and has for its object to provide a display device for show windows, etc., wherein, for example, a pyramid of cartons is to be represented which will appear like 15 actual cartons as to get up and size, but will in fact be made of cardboard and capable of being collapsed flat for shipment.

When cartons are to be displayed at present, the practice is either to use the actual 20 filled cartons or dump empty ones, or else a substitute for either of these is some times used in the form of a lithograph, purporting to represent a pyramid of cartons. The two former are objectionable because 25 of expense, shipping space required, while the latter does not convey the effect intended. By this invention a pyramid of rectangular cartons can be formed out of superposed box like structures which are externally

30 printed to resemble the actual cartons, which can be collapsed as a whole or in sections to be shipped flat. Moreover, in a three section pyramid, for example, as illustrated herein, each section is cut from one piece of card- 35 board, and the three sections are separably attached to each other. When the sections are detached each can be collapsed individually, and when assembled the entire structure can be collapsed as a unit without 40 disassembling the sections. The particular design herein illustrated lends itself further- more to economy of material used, both be- cause the patterns will nest closely together on the sheet, and also securing further econ- 45 omy in that the printing for the outside of the cartons will all go on the same side of the sheet, thereby necessitating only one printing. The device is herein shown in three sections, but the same principles can 50 be applied to a pyramid of as many sections as desired.

In the accompanying drawings,

Figure 1 shows the patterns for three sec- tions laid out flat and nested for cutting out, 55 Fig. 2 shows the complete device,

Fig. 3 shows the bottom section,

Fig. 4 the intermediate section,

Fig. 5 the top section,

Fig. 6 a plan view showing one side of the device when collapsed, and

Fig. 7 the view of the other side when collapsed.

1 represents a base section, 2 an inter- 60 mediate section and 3 the top section, the patterns for each respectively are indicated by corresponding numbers 1, 2, 3, in Fig. 1. As shown in Fig. 1, each piece is integral 65 and of progressively smaller generally L shaped outline thereby nesting economically on large sheets of cardboard or other sheet 70 material.

As herein shown the bottom section 1 rep- 75 presents a block corresponding to 9 cartons, the section 2 a block corresponding to 4 cartons and the section 3 a block corresponding to one carton. The section 1 comprises sides 4, 5, 6, 7, with scores 8 between to form 80 hinges and the tab 9, to be interiorly pasted to the inside of the section 4 to connect it with 7. 10 represents the top hinged by a score as at 11 to sections 4 and having di- 85 vision lines 12 on the upper surface to repre- sent the lines between cartons, these lines 12 continuing the vertical division lines be- 90 tween the sections 4, 5, 6, 7, when the sides 85 are brought around and connected and the top brought down thereon. Hinged to the top 10 as by score 13 opposite the score 11 is a flap 14 which is provided with two sup- 95 porting feet 15 which rest on the table or other support carrying the base 1 so as to support the top 10, see Fig. 3, the flap 14 passing down within and adjacent to the sides 4. Cut out from the flap 15 is a tongue 16 which will be scored at 17 to 95 provide the pasting flap 18 which will be secured to the bottom of the intermediate section 4 as shown at 19, Fig. 3, and scored as at 20 to provide a hinge. 21, 21 and 22, 100 22 are additional scores forming hinges for the links 23. The end section 24 of the flap is provided with spear heads 25 which pass through slots 26 in the section 10, and interlocked therewith, so as to form a center support for the top, this center support ex- 105 tends from the upper edge of end section 24 to the score 20, as will be seen in Fig. 3 by carrying the top 10 and the associated parts down inside the side sections 4, 5, 6, 7.

A section such as section 1 will collapse 110

flat without disengaging the spear heads 25 from slots 26, it being seen that the slots 26 comprise straight portions with up-turned ends, through which the spear heads 25 will 5 pass with slight bending of the sides of the spear heads and as soon as passed through they straighten out and hold the lock. They can be disengaged by slightly bending in and then pulling through the slot. This 10 particular locking comprises a feature of the invention, as so far as I am aware it is new, and has the functional advantage here that in folding flat the portion of material between the up-turned ends of the slot will 15 yield outwardly sufficient to allow flat folding without tearing or breaking.

The intermediate section 2 is somewhat similarly constructed comprising sides 30, 31, 32, 33 with a tab 34 to be pasted to the 20 end of 30. See Fig. 4. 35 represents the top hinged to section 30 by score 36 and having hinged to it the flap 37 by score 38. The sides 30 and the flap 37 carry spear heads 39 similar to 25, which pass through slots 40 in 25 top 10 for attaching the intermediate section 2. The slots 40 are similar to slots 26. As seen from Fig. 4 the flap 37 passes down inside of sides 32 so that the spear heads 39 lock section 2 to section 1.

30 The section 3 consists of sides 42, 43, 44, 45, with tab 46 to be attached to side 42, a top 47 hinged to side 42 by score 48 and carrying flap 49 hinged to 47 by score 50, the side 42 and the flap 49 carrying spear 35 heads 51 which pass through slots 52 in top 35, thus fastening section 3 to section 2. While these sections can be separately disconnected and separately folded flat as will be obvious, in order to save trouble of the 40 customer in setting them up it is preferable to ship them in assembled relation but folded flat. In order that these three sections will fold flat when assembled the tops must be hinged to corresponding sides in parallel planes, so that the three top hinges 11, 45 36, 48, are parallel. This will bring the hinges 13, 38, 50 of flaps 14, 37 and 49 parallel, the flaps in each instance passing within and adjacent the sides 6, 32, 44, respectively. In folding, the top 10 is lifted 50 up and swung on hinge 11 until in the same plane as sides 4, whereupon the flap 14 and associated links are flat against sides 4 and the top. The sides 5, 6, 7, can then be collapsed outwardly so as to cover the link 16.

55 The intermediate section now collapses by its top 35 passing down inside its sides 30, 31, 32, 33, while at the same time the top 47 passes down inside sides 42, 43, 44, 45. This 60 brings the latter 4 sides partly within the sides 30—33, whereupon both are collapsed flat on top of the previously collapsed section, thus collapsing the entire device in one piece, Figs. 6 and 7 showing the collapsed relation.

It will be seen from inspection of Fig. 1 that necessary printing, scoring, etc., can all be done in one operation so that the cost of manufacture of the device will be very small in comparison with the amount of saving to be effected for display purposes in using this device instead of empty or filled cartons.

70 The invention is susceptible of various modifications and changes and I do not restrict myself to the particular shapes and dimensions shown herein, nor to the use of scores, as same may be widely varied without departing from the scope of the appended claims.

75 What I claim is:

1. A collapsible display device in the form of a stepped pyramid, comprising a plurality of sections constituting the respective steps of the pyramid and each adapted 80 to fold flat, and means for attaching each of said sections to the top of the section immediately beneath it, said attaching means permitting collapse of the assembled sections.

2. A collapsible section for a carton device comprising sides hinged to fold flat, and a top hinged to one of the sides and arranged to fold outwardly thereof when the sides are collapsed, the top carrying at 90 the edge opposite the hinge a depending loose flap of sufficient length to constitute an independent support for said edge.

3. A carton device comprising a base section composed of sides connected together 100 and a top, a top section comprising a top and connected sides attached to the top of the base section, the respective tops being hinged on the respective sections, and the opposite sides of the tops being free to 105 swing as the sides are collapsed.

4. A carton device comprising a base section composed of sides connected together and a top, a top section comprising a top and connected sides attached to the top of the base section, the respective tops being hinged on the respective sections, and the opposite sides of the tops being free to swing as the sides are collapsed, and a supporting flap carried by each top to extend 110 adjacent one side for supporting that top and its associated sides against collapse.

5. In a collapsible carton display device, connected sides hinged to fold flat, a top hinged to one of the sides, and a flap hinged 115 to the top and adapted to lie adjacent the side opposite the one carrying the hinge for preventing collapse of the sides, and being of sufficient length to constitute an independent support for the top.

120 6. A carton device comprising a base section composed of sides connected together and a top, a top section comprising a top and connected sides attached to the top of the base section, the respective tops being 125

- hinged on the respective sections, and the opposite sides of the tops being free to swing as the sides are collapsed, the side carrying the hinge and the flap having ends formed 5 to interlock with a supporting base.
7. In a collapsible carton display device, a base section comprising hinged sides, a top hinged to one side, a flap carried by the top on the side opposite the hinge, for supporting the edge of the top, and a central support for the top carried by the flap.
8. In a collapsible carton display device, a base section comprising hinged sides, a top hinged to one side, a flap carried by the top 10 on the side opposite the hinge, for supporting the edge of the top and a central support for the top carried by the flap separably engaging the top and when disengaged permitting the top and sides to be collapsed.
9. In a collapsible carton display device, a base section comprising hinged sides, a top hinged to one side, a flap carried by the top on the side opposite the hinge, for supporting the edge of the top and a central support for the top carried by the flap 15 separably engaging the top and when disengaged permitting the top and sides to be collapsed, and a hinge connection between the flap and the side to which the top is hinged.
10. A collapsible carton display device comprising a plurality of sections comprising a top and sides of progressively varying size, means separably securing each section 20 to the one below, such securing acting to lock the section against collapse and to support the top, and permitting the sections to be collapsed flat when disconnected.
11. In a collapsible sectional display device, means for separably attaching one section to another comprising a slot in one section having upturned ends, and a projecting spear head tongue on the other section adapted to pass through said slot by bending, and to spring back when passed through 25 to lock.
12. A three piece carton display device comprising a collapsible bottom section comprised of hinged sides and a top hinged to one side and having a depending supporting flap, the flap carrying a hinged center support separably interlocking with the top, a collapsible section separably mounted thereon comprising sides and top, and a collapsible top section separably carried by said 30 last section.
13. A collapsible carton device comprising a plurality of stacked collapsible sections each having hinged sides and tops hinged to one of the sides in parallel planes, and means for supporting each top so that when moved on its hinges relatively to the sides, the sides and top collapse flat.

Signed at New York city, in the county of New York and State of New York, this 18th day of December, A. D. 1920.

GORDON KAY.
